US00D994017S

(12) **United States Design Patent** (10) **Patent No.:** **US D994,017 S**
Sun (45) **Date of Patent:** **** Aug. 1, 2023**

(54) **PAPER SHREDDER**

(71) Applicant: **DONGGUAN SUNTECH ELECTRONICS CO., LTD.**,
 Dongguan (CN)

(72) Inventor: **Yicheng Sun**, Dongguan (CN)

(73) Assignee: **DONGGUAN SUNTECH ELECTRONICS CO., LTD.**,
 Dongguan (CN)

(**) Term: **15 Years**

(21) Appl. No.: **29/790,523**

(22) Filed: **Dec. 2, 2021**

(30) **Foreign Application Priority Data**

Nov. 24, 2021 (EM) 008772156-0002

(57) **CLAIM**

The ornamental design for a paper shredder, as shown and described.

DESCRIPTION

FIG. 1 is a perspective view of a paper shredder, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the shredder that forms no part of the claimed design.

1 Claim, 8 Drawing Sheets
